UNITED STATES PATENT OFFICE.

GEORGE SHARPE RAMSAY, OF ST. MARYS, PENNSYLVANIA.

COAL-WASHER.

No. 811,871.

Specification of Letters Patent.

Patented Feb. 6, 1906.

Application filed October 10, 1903. Serial No. 176,569.

To all whom it may concern:

Be it known that I, GEORGE SHARPE RAMSAY, a citizen of the United States, residing at St. Marys, in the county of Elk and State 5 of Pennsylvania, have invented a new and useful Coal-Washer, of which the following is a specification.

The invention relates to improvements in coal-washers.

10 The object of the present invention is to improve the construction of coal-washers and to provide a simple, inexpensive, and efficient one capable of automatically separating sulfur, slate, rock, bone, and other 15 heavy impurities from the coal and adapted to deliver the clean coal into a bin or other receptacle and to discharge the refuse into a sluice-chute or other receptacle for causing the said refuse to be carried away by water 20 or gravity.

A further object of the invention is to provide a coal-washer of this character having a sluiceway which will not be corroded or similarly injured by the sulfur and other material 25 contained in the coal.

Another object of the invention is to improve the construction of the coal-washing means and to enable the water to be used again and again and at the same time permit 30 the character of the washing to be readily ascertained.

With these and other objects in view the invention consists in the construction and novel combination and arrangement of parts 35 hereinafter fully described, illustrated in the accompanying drawings, and pointed out in the claims hereto appended, it being understood that various changes in the form, proportion, size, and minor details of construction 40 within the scope of the claims may be resorted to without departing from the spirit or sacrificing any of the advantages of the invention.

In the drawings, Figure 1 is a longitudinal 45 sectional view of the upper portion of the apparatus. Fig. 2 is a similar view of the lower portion of the apparatus. Fig. 3 is a transverse sectional view on the line 3 3 of Fig. 1. Fig. 4 is a similar view on the line 4 4 of Fig. 50 1. Fig. 5 is a detail view of a portion of the lower spout or chute. Fig. 6 is a detail view illustrating the construction of the scrapers.

Like numerals of reference designate corresponding parts in all the figures of the drawings.

55 1 designates a sluice-box supported by a

suitable framework and composed of a bottom 2 and sides 3 and provided with a bottom lining 4, of plate glass or other suitable material of a similar nature which will not 60 be affected by the sulfur and other material found in coal, whereby the bottom of the sluice-box is prevented from corroding. The glass presents a smooth hard surface and is free from irregularities and is adapted to re- 65 tain the true flush character and form of its surface longer than wood or metal. The sides of the sluice-box are also provided with linings 5, which, however, may be constructed either of glass or sheet metal, as the sulfur 70 and other material found in coal and liable to corrode the sheet metal will not contact sufficiently with the side linings to require the same to be constructed of non-corrodible material. The side linings 5 are inclined up- 75 wardly and outwardly, and any means may be provided for connecting the side and bottom linings to form a water-tight joint or connection for preventing the sluice-box from leaking. The bottom lining, besides being non-corrodible, presents a smooth upper surface and will not be worn by the heavy 80 refuse material and the coal.

The sluice-box is arranged at a slight inclination, as clearly illustrated in Figs. 1 and 85 2 of the drawings, and the coal to be cleaned is in the form of dust or powdered material and is delivered to the sluice-box at a point between the ends thereof by means of a coal-chute 6, arranged at an inclination and pro- 90 vided with an enlarged upper portion or hopper, as clearly shown in Fig. 1.

Within the sluice-box is arranged a lower flight of an endless conveyer, which is composed of a pair of endless chains 7 and trans- 95 verse scrapers 8, arranged at intervals and connecting the chains. The chains are provided at intervals with links 9, having projecting portions or brackets 10, forming seats for the scrapers. The projecting por- 100 tions or brackets consist of flanges arranged approximately at right angles and forming a recess for the scrapers. The brackets are located at the centers of the links, as clearly shown in Fig. 6, whereby the scrapers are 105 caused to maintain a proper contact with the bottom of the sluiceway and are prevented from tilting the links, and thereby affecting such contact with the glass bottom. Each scraper consists of a body portion 12, of hard 110 wood or other suitable material, a strip 13 of rubber or gum or other elastic material, and

a metallic strip 14, arranged on the outer face of the elastic strip for protecting and supporting the same. The scraper is secured to the projecting flanges of the brackets by bolts 5 15 or other suitable fastening devices, which pass through perforations of the projecting flanges and through the body portion of the scraper and the elastic metallic strips. The wooden body portion has its front face 16 inclined backward from the direction of advance of the scraper to receive the elastic strip, which is also inclined in the same direction, and the lower face 16^a of the body portion is spaced from the bottom of the sluiceway and is inclined. The inclined front or 10 engaging portion of the scraper permits the coal to be floated or carried over it by the water and at the same time prevents any of the heavier material from escaping. The inclined sides 5 of the sluiceway prevent any 15 clogging of the material, as any upward movement of the same caused by the scrapers will operate to loosen the material, owing to the gradual increase in width of the sluiceway from the bottom to the top of the inclined sides. By inclining the flexible strip 20 backward from the direction of advance of the scrapers there is a tendency to compress, as well as flex, the exposed projecting portion 25 of the elastic strip, which is braced or stiffened and enabled to operate more effectively than a vertical strip, which would be easily bent or flexed backward. The elastic strip, which 30 projects beyond the wooden body portion, has its edge engaging the glass bottom-lining and also the side linings, and it causes the 35 water and coal to flow over the scrapers and pass downward to the lower end of the sluiceway, and at the same time the scrapers carry 40 forward or upward in the opposite direction all deleterious material lying upon the bottom of the sluice-box. The water, which moistens and in a sense lubricates both the 45 glass bottom and the yieldable portion of the scraper, causes the latter to adhere to the glass bottom, and as the projecting yieldable portion of the scraper is moved forwardly or upwardly along the said bottom the glass is 50 cleaned of all material lying upon it and not floated over the scraper by the action of the water, and such refuse material will be carried forward and effectually prevented from 55 passing under the scrapers.

The endless chains are arranged on 55 sprocket-wheels 17 and 18, disposed in pairs at the ends of the sluice-box and mounted on suitable shafts 19 and 20. The shafts 19 and 20 are journaled in suitable bearings of the sides of the sluice-box, and any suitable 60 power may be connected with either of the shafts for operating the endless conveyer. A sprocket-wheel 19^a is preferably mounted on the lower shaft 19, as indicated in Fig. 2 of the drawings.

65 The sluice-box is provided at intervals

with uprights 21, located at opposite sides of the sluiceway and supporting transverse bars or beams 22, upon which are mounted opposite longitudinal stringers 23, provided at their upper faces with strips 24 of steel or 70 other suitable material. The strips of steel form guides for supporting the upper flight of the endless conveyer and their terminals are extended beyond the stringers and inclined downwardly, as shown at 25, to prevent the links of the chains from catching on the ends of the guides. The sluice-box is provided at its upper portion with transverse water-supply pipes 26, 27, and 28. The pipes 26 and 27, which are of greater diameter than the pipes 28, are connected with suitable means for pumping the water back again after the same has passed through the sluiceway, the water being designed to be used over and over again. The smaller pipe 80 28 is designed to supply clear water to enable the slate, which is carried upward by the conveyer, to be readily examined to ascertain whether the washer is working properly. The washer is provided beneath the water-pipes with inclined plates or spreaders 30, consisting of inclined planes constructed of wood or other suitable material and adapted to receive and spread the water flowing from the water-supply pipes. The water-supply 90 pipes may be provided with one or more apertures, and the inclined spreading devices will cause the water to spread over the sluice-box and effectively wash the coal.

The lower end of the sluice-box is provided 100 with an inclined chute or spout 31 for discharging clean coal into a bin or receptacle. The inclined faces of the transverse scrapers assist in floating the coal over them, and as the heavy impurities—such as sulfur, slate, 105 rock, and bone—sink to the bottom of the sluiceway the scrapers will engage the same and automatically separate such impurities from the coal by carrying them forwardly or upwardly to a discharge-opening 32. The 110 discharge-opening 32 receives the upper end of an inclined chute or skid 33, which extends downwardly for directing the refuse away from the sluice-box. By this means the refuse is discharged into a sluice-chute or 115 other receptacle at one end of the apparatus, whereby the refuse is carried away by water or gravity.

It will be seen that the coal-washer is exceedingly simple and inexpensive in construction, that it is capable of effectively separating the heavy impurities—such as sulfur, slate, 120 rock, and bone—from the coal, and that the pure coal and the heavy impurities are carried in opposite directions and discharged at opposite ends of the apparatus. Also it will be clear that the glass lining at the bottom of the sluiceway is non-corrodible and at the same time presents a smooth surface, whereby 125 the bottom of the sluiceway is prevented 130

from being corroded or worn by the sulfur and heavy impurities. Furthermore, it will be clear that the transverse scraper, which conforms to the configuration of the lower portion of the sluiceway, is adapted to cause the water to flow over it and that the elastic strip sweeps the material forwardly and prevents any of the sulfur or other heavy impurities from passing beneath it or around it.

Having thus fully described my invention, what I claim as new, and desire to secure by Letters Patent, is—

1. A coal-washer, comprising a sluiceway, an endless belt or belts, and scrapers carried by the endless belt or belts and composed of a body portion arranged to clear the sluiceway, an inclined strip of yieldable material arranged on the front face of the body portion and inclined backwardly from the direction of advance of the scrapers and having its edge engaging the bottom of the sluiceway, and means for securing the strip of yieldable material to the said body portion.

2. A coal-washer, comprising a sluiceway, sprocket-wheels, endless chains having brackets arranged at intervals and provided with seats and projecting flanges, and scrapers mounted in the seats of the brackets and supported by the flanges thereof and composed of a body portion arranged to clear the sluiceway and having its front inclined backward from the direction of advance of the scrapers, an inclined elastic strip arranged on the front face of the body portion and supported by the same and having its edges engaging and adapted to be flexed by the sluiceway, and means for supporting the elastic strip.

3. A coal-washer, comprising a sluiceway having a glass bottom-lining presenting a smooth surface, an endless belt or belts provided with scrapers of yielding material engaging the glass bottom, and means for feeding material and water to the sluiceway, whereby both the scrapers and the glass bottom are wet and the former are caused to adhere to the latter.

4. A coal-washer, comprising a sluiceway having a glass bottom-lining presenting a smooth upper face, an endless belt or belts provided with scrapers operating in the sluiceway, said scrapers being provided with rigid bottom portions, yielding projecting portions engaging the glass lining, and means for supplying water to the sluiceway. 55

5. A coal-washer, comprising a sluiceway provided with a smooth bottom-lining of glass and having metallic side linings, an endless belt or belts provided with scrapers having projecting yieldable portions, the edges of the yieldable portions being engaged with the bottom and sides of the sluiceway, and means for supplying water to the sluiceway.

6. A coal-washer, comprising an inclined 65 sluiceway, scrapers operating in the sluiceway, a coal-chute discharging into the sluiceway, and a plurality of water-supply pipes arranged in spaced relation between the coal-chute and the upper end of the sluiceway, one 70 of the pipes being of reduced diameter and discharging clear water into the sluiceway near the upper end thereof to clarify the same and expose the material carried by the scrapers.

7. A coal-washer, comprising an inclined sluiceway, an endless belt or belts provided with scrapers operating in the sluiceway, and transversely-disposed water-supply pipes of different diameters, the larger pipe being 80 adapted to discharge water which has been used, and the smaller pipe being arranged at the upper portion of the sluiceway and discharging clear water to clarify the same and to expose to view the material carried by the 85 scrapers.

In testimony that I claim the foregoing as my own I have hereto affixed my signature in the presence of two witnesses.

GEORGE SHARPE RAMSAY.
